(57) CLAIM

The ornamental design for a hand held light, as shown and described.

DESCRIPTION

FIG. 1 is a front perspective view of a hand held light showing my new design;

FIG. 2 is a front elevation view of the invention illustrated in FIG. 1;

FIG. 3 is a rear elevation view of the invention illustrated in FIG. 1;

FIG. 4 is a left elevation view of the invention illustrated in FIG. 1;

FIG. 5 is a right elevation view of the invention illustrated in FIG. 1;

FIG. 6 is a top plan view of the invention illustrated in FIG. 1;

FIG. 7 is a bottom plan view of the invention illustrated in FIG. 1;

FIG. 8 is a front perspective view of the invention illustrated in FIG. 1 with the lighting element shown in a first open position; and,

FIG. 9 is a front perspective view of the invention illustrated in FIG. 1 with the lighting element shown in a second open position.
